Inventor

UNITED STATES PATENT OFFICE.

CHARLES G. ROBINSON, OF BUFFALO, NEW YORK, ASSIGNOR, BY MESNE ASSIGNMENTS, TO THE BEAVER PRODUCTS COMPANY, INC., A CORPORATION OF NEW YORK.

PAPER-MAKING APPARATUS.

Application filed November 24, 1919. Serial No. 340,296.

To all whom it may concern:

Be it known that I, CHARLES G. ROBINSON, a citizen of the United States, residing at 183 Highland Avenue, Buffalo, in the 5 county of Erie, State of New York, have invented certain new and useful Improvements in Paper-Making Apparatus; and I do hereby declare the following to be a full, clear, and exact description of the invention, such as will enable others skilled in the art to which it appertains to make and use the same.

This invention relates to improvements 15 in the manufacture of paper and involves an improved apparatus of the duplex type in which a common drying element is operatively associated with two independent instrumentalities for simultaneously forming two webs of paper from appropriate 20 paper pulp stock.

In its general aspect, the invention contemplates a duplex machine or apparatus which is adapted to simultaneously produce 25 two independent sheets or webs of paper. Thus, the improved apparatus of the invention comprises a complete paper making machine of the ordinary type in combination with the wet or forming end of a similar paper making machine, the latter being 30 arranged to utilize the drying element of the first paper making machine. In general, the complete paper making machine is constructed and arranged in accordance with the usual present day practice, and 35 with this machine is combined the wet or forming end of a second paper making machine. In practice, I find it convenient to arrange the second wet or forming end of the duplex apparatus at a higher level than 40 the other wet or forming end of the apparatus, for example, on the floor above. The two wet or forming ends of the duplex apparatus are arranged to deliver the formed webs of paper to the drying element. 45 From the drying element simultaneously of the duplex apparatus, the two sheets or dried webs of paper are conducted to independent calenders and from the respective calenders to winders, slitters, rewinders or 50 other appropriate finishing elements.

The novel features of the invention which I believe to be patentably characteristic thereof are set forth in the appended claim. The construction and mode of operation of the improved apparatus of the

invention will be better understood from the following description taken in conjunction with the accompanying drawings, in which—

Fig. 1 diagrammatically illustrates two 60 wet ends or web-forming devices for forming webs of paper from appropriate paper stock; and

Fig. 2 diagrammatically illustrates the common drying and finishing elements of 65 the duplex apparatus.

It will be understood that Fig. 2 of the accompanying drawings is in effect a continuation of Fig. 1, so that Fig. 1 is the left hand portion of the improved duplex 70 apparatus and Fig. 2 is the remainder or right-hand end of the duplex apparatus.

Referring now more particularly to the accompanying drawings, I have designated by reference character A the wet or forming end of an ordinary paper making machine and by reference character B the wet or forming end of a similar paper making machine and by reference character C the drying element of an ordinary paper making machine. The wet end A and the drying element C, together with the appropriate calenders, form in combination a paper making machine of the ordinary type, while the wet end B and the drying element C, 85 together with the appropriate calenders, form in combination a similar wet paper making machine of the ordinary type. In accordance with my preferred practice, the two wet or forming ends A and B are arranged one above the other, for example, on the first and second floors of the building in which the duplex apparatus is located.

The wet or forming ends A and B of the 95 duplex apparatus comprise appropriate instrumentalities for forming a web of paper from suitable paper pulp stock. In general, the construction and mode of operation of these instrumentalities may conform 100 to any of the accepted forms employed in the paper making industry and I have herein described a particular type of instrumentation merely for the purposes of explanation. While I prefer to arrange the two wet ends A and B at different levels, it will be understood that such arrangement is not an essential feature of the invention.

As diagrammatically represented in Fig. 110 1 of the accompanying drawings, each of

the wet ends A and B of the duplex apparatus comprises a series of pulp vats 10 within which are mounted screen cylinders 11 of the usual type. The pulp within the 5 vats is maintained at the desired level, as well understood in the art, so that the cylinders 11 will be immersed therein to the desired extent. The water passing into the interior of the cylinders 11 is withdrawn 10 therefrom in a manner well understood in the art and accordingly not herein illustrated and described. As the cylinders 11 rotate, a layer of pulp is formed thereon, the thickness of the pulp layer being regulated 15 by the difference in level between the pulp and the water within the cylinder. Arranged above each cylinder 11 is a couch roll 12 carried by a pivotally supported frame member 13. The distance or space 20 between the co-operating couch rolls 12 and cylinders 11 may be appropriately adjusted by means of a hand wheel 14 and co-operating link 15.

The paper making machine has a lower 25 felt or blanket 16 and an upper felt or blanket 17. These blankets are of the usual endless type and appropriate guide rolls and the like are provided in conjunction therewith, as well understood in the art. The 30 lower blanket 16 passes over the cylinders 11, and the layer of pulp formed upon each cylinder is brought into contact with the blanket as the cylinder rotates and is removed from the cylinder by the blanket 35 which carries it through the machine in the well understood manner.

The second felt or blanket 17 comes in contact with the layer or web of pulp adhering to the lower blanket 16 at the first of 40 a series of ringer rolls 18, so that the layer of pulp is in contact with both the upper and lower blankets when passing through the ringer rolls 18. These rolls serve to remove a portion of the water from the pulp 45 web. From the last of the ringer rolls 18, the web of pulp enclosed between the lower and upper blankets 16 and 17, respectively, passes downwardly to a series of press rolls 50 19 between which it is subjected to a heavy pressure, so that a large portion of the water is squeezed out of the pulp web. After passing through the last press roll 19, the upper blanket 17 is separated from the pulp web, and the lower blanket 16 and adhering 55 pulp web pass through the first of a series of presses 20. After passing through the first press 20 of the series, the lower blanket 16 is separated from the pulp web, and the pulp web then passes through the remaining presses of the series.

Referring now more particularly to Fig. 2 of the drawings, it will be observed that the web of pulp coming from the fourth press or press rolls of either of the wet ends 60 A or B of the paper making apparatus

passes through suitable guide and press rolls 21 and thence into the common drying element of the apparatus. As well understood in the art, the drying element comprises a series of drying rolls which are diagrammatically indicated in Fig. 2 of the drawings by reference character 22. From the drying element, the two webs of paper pass to independent calenders 23 and 24. Thus, it will 70 be understood that the calenders 23 are arranged to receive the web or sheet of paper formed in the wet end A of the apparatus, while the calenders 24 are similarly arranged to receive the sheet or web of paper formed in the wet end B of the apparatus. 80 A winder 25, a slitter 26, and a rewinder 27 are operatively associated with the calender 23, and similarly a winder 28, a slitter 29 and a rewinder 30 are operatively associated with the calender 24. The winders and 85 slitters may be of the usual type.

From the foregoing description, it will be understood that two webs of paper are simultaneously formed in the forming instrumentalities A and B. After expressing 90 an appropriate amount of moisture from each of these pulp webs, the two webs of pulp are conducted together through the drying element C of the duplex apparatus. In this manner, the capacity of the drying element is substantially doubled, since two sheets or webs of pulp are simultaneously dried in the drying element C. After passing through the drying element C, the two sheets or webs of dried pulp are passed to 95 independent calenders and subsequently to independent winders, slitters, and rewinders. In this manner, a common drying element is employed in combination with two independent instrumentalities for forming 100 webs of pulp from appropriate paper pulp stock. Thus, in accordance with the arrangement of the invention, two sheets of paper are simultaneously formed and run through the duplex machine and over the 105 common driers at the same time, the two sheets separating at the end of the common drier and running through separate calenders and suitable finishing devices. Such an arrangement is very economical in operation, since it enables a material decrease in 110 the amount of capital investment, and results in increased production without a disproportionate increase in the amount of additional machinery required.

Having thus described my invention, what I claim is:

In a paper making apparatus, the combination of a plurality of web forming mechanisms, each provided with a plurality of forming cylinders, said cylinders co-operating 125 with one another to form an integral wet paper web on a felt common to them all; each forming mechanism having means including pressers to reduce the moisture 130

content of the paper webs to an appropriate degree; said forming mechanisms being relatively long and being arranged one above the other to reduce the longitudinal space occupied by the entire apparatus and having their dry ends adjacent; a single set of drying cylinders over which the webs of paper from each of said forming mechanisms travel together; said pressing means being ad-

justed to remove sufficient moisture from 10 said webs to prevent sticking together when passing over the drying cylinders; and means beyond said drying cylinders for separating and for separately calendering and winding the resultant paper webs. 15

In testimony whereof I affix my signature.

CHARLES G. ROBINSON.

Certificate of Correction.

It is hereby certified that in Letters Patent No. 1,503,246, granted July 29, 1924, upon the application of Charles G. Robinson, of Buffalo, New York, for an improvement in "Paper-Making Apparatus," an error appears in the printed specification requiring correction as follows: Page 1, line 45, strike out the word "simultaneously" and insert the same to follow after the word "element" in line 44; and that the said Letters Patent should be read with this correction therein that the same may conform to the record of the case in the Patent Office.

Signed and sealed this 2d day of September, A. D. 1924.

[SEAL.]

KARL FENNING,
Acting Commissioner of Patents.
